UNITED STATES PATENT OFFICE.

JOHN CLARK HARTMAN, OF WATERLOO, IOWA.

VENT.

SPECIFICATION forming part of Letters Patent No. 437,988, dated October 7, 1890.

Application filed April 24, 1890. Serial No. 349,279. (No model.)

To all whom it may concern:

Be it known that I, JOHN CLARK HARTMAN, a citizen of the United States, residing at Waterloo, in the county of Black Hawk and State 5 of Iowa, have invented certain new and useful Improvements in Vents; and I do declare the following to be a full, clear, and exact description of the invention, such as will enable others skilled in the art to which it 10 appertains to make and use the same, reference being had to the accompanying drawings, and to the letters of reference marked thereon, which form a part of this specification.

15 My invention relates to vents for closed vessels.

The object of my improvements is to provide a vent-opening for portable cans, jars, or the like, which may be readily uncovered 20 or unsealed during the operation of emptying such vessels.

25 For this purpose my invention consists in the following construction and combination of parts, which will first be fully described, and the features of novelty then set forth in the claim.

30 Figure 1 is a sectional view of a cap or closure for cans or the like to which my improvements have been applied. Fig. 2 is a similar view showing a modification of my invention. Fig. 3 is a sectional view of a portion of a can, showing still another modification of my improvements. Fig. 4 is a view similar to Figs. 1 and 2, showing yet another 35 modified form embodying my invention.

In Fig. 1, *a* represents an ordinary screw-cap for oil-cans. *b* is a central perforation in the top of the cap, through which projects the valve-stem *c*. *e* is a guide-frame riveted or 40 otherwise secured to the under side of the cap, and within which the lower end of the valve-stem is stepped in sliding ways. *f* is the valve which closes the vent-opening *b*. This valve rests normally against the under 45 side of the cap. *g* is a spiral spring surrounding the valve-stem *c* and bearing against the underside of the valve at one end and against the guide-frame at the other. This spring has a constant tendency to seat the valve.

against the under side of the cap. *h h* are 50 notches formed on opposite sides of the valve-stem near its upper end.

A shoulder *p* or stop is formed on the valve-stem *c*, Figs. 1 and 2, adapted to strike the frame *e* and limit the movement of the stem, 55 whereby it may not be pushed down so far that the thumb or finger would close the vent *b*.

Pressing down on the top of the valve unseats the valve, and the spring being 60 compressed has a tendency to throw the valve-stem to one side or the other when the notches *h h* come abreast or opposite the vent-opening *b* and uncover said opening, the spring holding the stem in that position. To reseal 65 the vent, the valve-stem is pushed back into line with the vent-opening, when the spring again seats the valve.

The valve-stem in Fig. 1 is approximately 70 rectangular in cross-section. It may, however, be of other form, and the slots *h h* be continued clear around the stem in an annular groove. In Fig. 2 the parts are substantially the same, except that the valve-stem is cylindrical, as is also the vent-opening. Above 75 the vent-opening when the valve is seated the valve-stem is cut away, as shown at *i i*, to allow a free passage of air when the valve-stem is depressed and the parts *i i* come abreast the vent.

In Fig. 3 my invention is shown applied to the body of a can direct. *k* is a wire spring attached to the interior of a can at one end and the other carrying a valve *l* and short valve-stem *m*, projecting from the upper side 85 thereof and through the vent-opening. In Fig. 4 a similar construction is shown applied to a cap for cans. In this modification the spring *o* for normally closing the vent is a flat short spring.

In all the modifications I prefer to use a paper washer upon the face of the valve or valve-seat, such as will not be affected by the fumes of oil or other liquids. Other material which will answer this purpose could be used. 90

I may apply my invention to any vessel to which it may be adapted, either to the vessel itself or to its cap or cover.

I claim as new and desire to secure by Letters Patent—

The combination of a valve, a valve-stem, a can or can-closure provided with a valve-seat, a spring normally seating the valve, and 5 a notch on the valve-stem, adapted to engage the valve-seat.

In testimony whereof I affix my signature in presence of two witnesses.

JOHN CLARK HARTMAN.
